(57) **ABSTRACT**

A method of operating a washing machine appliance includes initiating a spin cycle by operating the motor to spin the wash basket to a first speed, performing a first acceleration by operating the motor to accelerate the wash basket from the first speed to a second speed, obtaining a first average motor power of the motor while performing the first acceleration, decelerating the wash basket to the first speed, performing a second acceleration by operating the motor to accelerate the wash basket from the first speed to the second speed, obtaining a second average motor power of the motor while performing the second acceleration, and stopping the spin cycle in response to determining that a reduction in a remaining moisture content exceeds a target reduction in the remaining moisture content based at least in part on the first average motor power and the second average motor power.

FIG. 1

FIG. 2

FIG. 4

FIG. 5

FIG. 6

METHOD OF SENSING REMAINING MOISTURE CONTENT IN A WASHING MACHINE APPLIANCE

FIELD OF THE INVENTION

The present disclosure relates generally to top load washing machines, in particular a method of operating a top loading washing machine to monitor remaining moisture content during a spin cycle.

BACKGROUND OF THE INVENTION

Washing machine appliances generally include a cabinet which supports a wash tub for containing wash fluid, e.g., wash water, detergent, bleach, and/or other wash additives. A wash basket is mounted within the wash tub and defines a wash chamber for receipt of articles for washing. During operation of such washing machine appliances, wash fluid is directed into the wash tub and onto articles within the wash chamber of the wash basket. The wash basket or an agitation element can rotate at various speeds to agitate articles within the wash chamber in the wash fluid. A spin cycle is often included after some cycles, for example at the end of a wash cycle or a rinse cycle. During the spin cycle, the wash basket spins at a high speed to urge wash fluid from articles within the wash chamber.

Most conventional washing machines have user-selectable "spin" settings that will execute the same spin time for a clothing load regardless of fabric type or load size. A user who wants a shorter cycle may be able to select "low" spin for instance, which may reduce spin time and/or speed. However, this may result in a load that is not properly dried, which increases dryer energy usage. Another user may want their clothing load to be as dry as possible, so they select "Max" spin. Although their load may only need a certain amount of spin time to achieve optimal dryness, the washer will still spin according to their selection. Conventional washing machines do not have a method for detecting the actual dryness of the clothes before stopping the cycle. This can have an impact on component reliability (e.g., spinning longer wears out drive and suspension components) and energy (e.g., loads not spun out for enough time increase dryer energy usage).

Accordingly, a method of sensing the remaining moisture content of a load of clothes would be desirable. More specifically, a system for sensing the RMC and facilitating efficient and effective spin cycles in a washing machine would be particularly beneficial.

BRIEF DESCRIPTION OF THE INVENTION

Aspects and advantages of the invention will be set forth in part in the following description, may be apparent from the description, or may be learned through practice of the invention.

In one exemplary embodiment, a washing machine appliance defining a vertical direction, a lateral direction, and a transverse direction is provided, including a wash tub positioned within a cabinet, a wash basket rotatably mounted within the wash tub for receiving a load of clothes, a motor mechanically coupled to the wash basket, and a controller operably coupled to the motor. The controller is configured to initiate a spin cycle by operating the motor to spin the wash basket to a first speed, perform a first acceleration by operating the motor to accelerate the wash basket from the first speed to a second speed, obtain a first average motor

power of the motor while performing the first acceleration, decelerate the wash basket to the first speed, perform a second acceleration by operating the motor to accelerate the wash basket from the first speed to the second speed, obtain a second average motor power of the motor while performing the second acceleration, determine that a reduction in a remaining moisture content of the load of clothes exceeds a target reduction in the remaining moisture content based at least in part on the first average motor power and the second average motor power, and stop the spin cycle in response to determining that the reduction in the remaining moisture content exceeds the target reduction in the remaining moisture content.

In another exemplary embodiment, a method of operating a washing machine appliance is provided, the washing machine appliance comprising a wash tub positioned within a cabinet, a wash basket rotatably mounted within the wash tub for receiving a load of clothes, and a motor mechanically coupled to the wash basket. The method includes initiating a spin cycle by operating the motor to spin the wash basket to a first speed, performing a first acceleration by operating the motor to accelerate the wash basket from the first speed to a second speed, obtaining a first average motor power of the motor while performing the first acceleration, decelerating the wash basket to the first speed, performing a second acceleration by operating the motor to accelerate the wash basket from the first speed to the second speed, obtaining a second average motor power of the motor while performing the second acceleration, determining that a reduction in the remaining moisture content of the load of clothes exceeds a target reduction in the remaining moisture content based at least in part on the first average motor power and the second average motor power, and stopping the spin cycle in response to determining that the reduction in the remaining moisture content exceeds the target reduction in the remaining moisture content.

These and other features, aspects and advantages of the present invention will become better understood with reference to the following description and appended claims. The accompanying drawings, which are incorporated in and constitute a part of this specification, illustrate embodiments of the invention and, together with the description, serve to explain the principles of the invention.

BRIEF DESCRIPTION OF THE DRAWINGS

A full and enabling disclosure of the present invention, including the best mode thereof, directed to one of ordinary skill in the art, is set forth in the specification, which makes reference to the appended figures.

FIG. 1 provides a perspective view of a washing machine appliance according to an example embodiment of the present subject matter with a lid in a closed position.

FIG. 2 provides a perspective view of the example washing machine appliance of FIG. 1 with the lid of the washing machine appliance shown in an open position according to an example embodiment of the present subject matter.

FIG. 3 provides a side cross-sectional view of the example washing machine appliance of FIG. 1 according to an example embodiment of the present subject matter.

FIG. 4 illustrates a method of performing an automated spin cycle in a washing machine appliance according to an example embodiment of the present subject matter.

FIG. 5 is a plot of a basket speed and a motor power during an automated spin cycle according to an example embodiment of the present subject matter.

FIG. 6 is a plot of a motor power and a remaining moisture content during an automated spin cycle according to an example embodiment of the present subject matter.

Repeat use of reference characters in the present specification and drawings is intended to represent the same or analogous features or elements of the present invention.

DETAILED DESCRIPTION OF THE INVENTION

Reference now will be made in detail to embodiments of the invention, one or more examples of which are illustrated in the drawings. Each example is provided by way of explanation of the invention, not limitation of the invention. In fact, it will be apparent to those skilled in the art that various modifications and variations can be made in the present invention without departing from the scope or spirit of the invention. For instance, features illustrated or described as part of one embodiment can be used with another embodiment to yield a still further embodiment. Thus, it is intended that the present invention covers such modifications and variations as come within the scope of the appended claims and their equivalents.

As used herein, the terms "first," "second," and "third" may be used interchangeably to distinguish one component from another and are not intended to signify location or importance of the individual components. The terms "includes" and "including" are intended to be inclusive in a manner similar to the term "comprising." Similarly, the term "or" is generally intended to be inclusive (i.e., "A or B" is intended to mean "A or B or both"). In addition, here and throughout the specification and claims, range limitations may be combined and/or interchanged. Such ranges are identified and include all the sub-ranges contained therein unless context or language indicates otherwise. For example, all ranges disclosed herein are inclusive of the endpoints, and the endpoints are independently combinable with each other. The singular forms "a," "an," and "the" include plural references unless the context clearly dictates otherwise.

Approximating language, as used herein throughout the specification and claims, may be applied to modify any quantitative representation that could permissibly vary without resulting in a change in the basic function to which it is related. Accordingly, a value modified by a term or terms, such as "generally," "about," "approximately," and "substantially," are not to be limited to the precise value specified. In at least some instances, the approximating language may correspond to the precision of an instrument for measuring the value, or the precision of the methods or machines for constructing or manufacturing the components and/or systems. For example, the approximating language may refer to being within a 10 percent margin, i.e., including values within ten percent greater or less than the stated value. In this regard, for example, when used in the context of an angle or direction, such terms include within ten degrees greater or less than the stated angle or direction, e.g., "generally vertical" includes forming an angle of up to ten degrees in any direction, e.g., clockwise or counterclockwise, with the vertical direction V.

The word "exemplary" is used herein to mean "serving as an example, instance, or illustration." In addition, references to "an embodiment" or "one embodiment" does not necessarily refer to the same embodiment, although it may. Any implementation described herein as "exemplary" or "an embodiment" is not necessarily to be construed as preferred or advantageous over other implementations. Moreover, each example is provided by way of explanation of the

invention, not limitation of the invention. In fact, it will be apparent to those skilled in the art that various modifications and variations can be made in the present invention without departing from the scope of the invention. For instance, features illustrated or described as part of one embodiment can be used with another embodiment to yield a still further embodiment. Thus, it is intended that the present invention covers such modifications and variations as come within the scope of the appended claims and their equivalents.

FIGS. 1 through 3 illustrate an exemplary embodiment of a vertical axis washing machine appliance 100. Specifically, FIGS. 1 and 2 illustrate perspective views of washing machine appliance 100 in a closed and an open position, respectively. FIG. 3 provides a side cross-sectional view of washing machine appliance 100. Washing machine appliance 100 generally defines a vertical direction V, a lateral direction L, and a transverse direction T, each of which is mutually perpendicular, such that an orthogonal coordinate system is generally defined.

While described in the context of a specific embodiment of vertical axis washing machine appliance 100, it should be appreciated that vertical axis washing machine appliance 100 is provided by way of example only. It will be understood that aspects of the present subject matter may be used in any other suitable washing machine appliance, such as a horizontal axis washing machine appliance. Indeed, modifications and variations may be made to washing machine appliance 100, including different configurations, different appearances, and/or different features while remaining within the scope of the present subject matter.

Washing machine appliance 100 has a cabinet 102 that extends between a top portion 104 and a bottom portion 106 along the vertical direction V, between a first side (left) and a second side (right) along the lateral direction L, and between a front and a rear along the transverse direction T. As best shown in FIG. 3, a wash tub 108 is positioned within cabinet 102, defines a wash chamber 110, and is generally configured for retaining wash fluids during an operating cycle. Washing machine appliance 100 further includes a primary dispenser or dispensing assembly 112 (FIG. 2) for dispensing wash fluid into wash tub 108.

In addition, washing machine appliance 100 includes a wash basket 114 that is positioned within wash tub 108 and generally defines an opening 116 for receipt of articles for washing. More specifically, wash basket 114 is rotatably mounted within wash tub 108 such that it is rotatable about an axis of rotation A. According to the illustrated embodiment, the axis of rotation A is substantially parallel to the vertical direction V. In this regard, washing machine appliance 100 is generally referred to as a "vertical axis" or "top load" washing machine appliance 100. However, it should be appreciated that aspects of the present subject matter may be used within the context of a horizontal axis or front load washing machine appliance as well.

As illustrated, cabinet 102 of washing machine appliance 100 has a top panel 118. Top panel 118 defines an opening (FIG. 2) that coincides with opening 116 of wash basket 114 to permit a user access to wash basket 114. Washing machine appliance 100 further includes a door 120 which is rotatably mounted to top panel 118 to permit selective access to opening 116. In particular, door 120 selectively rotates between the closed position (as shown in FIGS. 1 and 3) and the open position (as shown in FIG. 2). In the closed position, door 120 inhibits access to wash basket 114. Conversely, in the open position, a user can access wash basket 114. A window 122 in door 120 permits viewing of wash basket 114 when door 120 is in the closed position,

e.g., during operation of washing machine appliance 100. Door 120 also includes a handle 124 that, e.g., a user may pull and/or lift when opening and closing door 120. Further, although door 120 is illustrated as mounted to top panel 118, door 120 may alternatively be mounted to cabinet 102 or any other suitable support.

As best shown in FIGS. 2 and 3, wash basket 114 further defines a plurality of perforations 126 to facilitate fluid communication between an interior of wash basket 114 and wash tub 108. In this regard, wash basket 114 is spaced apart from wash tub 108 to define a space for wash fluid to escape wash chamber 110. During a spin cycle, wash fluid within articles of clothing and within wash chamber 110 is urged through perforations 126 wherein it may collect in a sump 128 defined by wash tub 108. Washing machine appliance 100 further includes a pump assembly 130 (FIG. 3) that is located beneath wash tub 108 and wash basket 114 for gravity assisted flow when draining wash tub 108.

An impeller or agitation element 132 (FIG. 3), such as a vane agitator, impeller, auger, oscillatory basket mechanism, or some combination thereof is disposed in wash basket 114 to impart an oscillatory motion to articles and liquid in wash basket 114. More specifically, agitation element 132 extends into wash basket 114 and assists agitation of articles disposed within wash basket 114 during operation of washing machine appliance 100, e.g., to facilitate improved cleaning. In different embodiments, agitation element 132 includes a single action element (i.e., oscillatory only), a double action element (oscillatory movement at one end, single direction rotation at the other end) or a triple action element (oscillatory movement plus single direction rotation at one end, single direction rotation at the other end). As illustrated in FIG. 3, agitation element 132 and wash basket 114 are oriented to rotate about axis of rotation A (which is substantially parallel to vertical direction V).

As best illustrated in FIG. 3, washing machine appliance 100 includes a drive assembly or motor assembly 138 in mechanical communication with wash basket 114 to selectively rotate wash basket 114 (e.g., during an agitation or a rinse cycle of washing machine appliance 100). In addition, motor assembly 138 may also be in mechanical communication with agitation element 132. In this manner, motor assembly 138 may be configured for selectively rotating or oscillating wash basket 114 and/or agitation element 132 during various operating cycles of washing machine appliance 100.

More specifically, motor assembly 138 may generally include one or more of a drive motor 140 and a transmission assembly 142, e.g., such as a clutch assembly, for engaging and disengaging wash basket 114 and/or agitation element 132. According to the illustrated embodiment, drive motor 140 is a brushless DC electric motor, e.g., a pancake motor. However, according to alternative embodiments, drive motor 140 may be any other suitable type or configuration of motor. For example, drive motor 140 may be an AC motor, an induction motor, a permanent magnet synchronous motor, or any other suitable type of motor. In addition, motor assembly 138 may include any other suitable number, types, and configurations of support bearings or drive mechanisms.

Referring still to FIGS. 1 through 3, a control panel 150 with at least one input selector 152 (FIG. 1) extends from top panel 118. Control panel 150 and input selector 152 collectively form a user interface input for operator selection of machine cycles and features. A display 154 of control panel 150 indicates selected features, operation mode, a countdown timer, and/or other items of interest to appliance users regarding operation.

Operation of washing machine appliance 100 is controlled by a controller or processing device 156 that is operatively coupled to control panel 150 for user manipulation to select washing machine cycles and features. In response to user manipulation of control panel 150, controller 156 operates the various components of washing machine appliance 100 to execute selected machine cycles and features. According to an exemplary embodiment, controller 156 may include a memory and microprocessor, such as a general or special purpose microprocessor operable to execute programming instructions or micro-control code associated with methods described herein. Alternatively, controller 156 may be constructed without using a microprocessor, e.g., using a combination of discrete analog and/or digital logic circuitry (such as switches, amplifiers, integrators, comparators, flip-flops, AND gates, and the like) to perform control functionality instead of relying upon software. Control panel 150 and other components of washing machine appliance 100 may be in communication with controller 156 via one or more signal lines or shared communication busses.

During operation of washing machine appliance 100, laundry items are loaded into wash basket 114 through opening 116, and washing operation is initiated through operator manipulation of input selectors 152. Wash basket 114 is filled with water and detergent and/or other fluid additives via primary dispenser 112. One or more valves can be controlled by washing machine appliance 100 to provide for filling wash tub 108 and wash basket 114 to the appropriate level for the amount of articles being washed and/or rinsed. By way of example for a wash mode, once wash basket 114 is properly filled with fluid, the contents of wash basket 114 can be agitated (e.g., with agitation element 132 as discussed previously) for washing of laundry items in wash basket 114.

After completion of the agitation cycle, washing machine appliance 100 may perform one or more rinse cycles. Specifically, according to an example embodiment, drain pump assembly 130 may drain the wash fluid from wash tub 108 and dispensing assembly 112 may dispense fresh water and/or a wash additive (such as fabric softener) into the wash tub. The load of clothes may then be agitated in the fresh water, e.g., to remove soil and detergent from load of clothes. After completion of the rinse cycle(s), drain pump assembly 130 may drain wash tub 108 and a spin cycle may be used to extract water from the clothes before the wash cycle is concluded.

Referring again to FIGS. 2 and 3, dispensing assembly 112 of washing machine appliance 100 will be described in more detail. As explained briefly above, dispensing assembly 112 may generally be configured to dispense wash fluid to facilitate one or more operating cycles or phases of an operating cycle (e.g., such as a wash cycle or a rinse cycle). The terms "wash fluid" and the like may be used herein to generally refer to a liquid used for washing and/or rinsing clothing or other articles. For example, the wash fluid is typically made up of water that may include other additives such as detergent, fabric softener, bleach, or other suitable treatments (including combinations thereof). More specifically, the wash fluid for a wash cycle may be a mixture of water, detergent, and/or other additives, while the wash fluid for a rinse cycle may be water only and/or additional rinse additives.

As best shown schematically in FIG. 3, dispensing assembly 112 may generally include a bulk storage tank or bulk reservoir 158 and a dispenser box 160. More specifically, bulk reservoir 158 may be positioned under top panel 118 and defines an additive reservoir for receiving and storing

wash additive. More specifically, according to the illustrated embodiment, bulk reservoir 158 may contain a bulk volume of wash additive (such as detergent or other suitable wash additives) that is sufficient for a plurality of wash cycles of washing machine appliance 100, such as no less than twenty wash cycles, no less than fifty wash cycles, etc. As a particular example, bulk reservoir 158 is configured for containing no less than twenty fluid ounces, no less than three-quarters of a gallon, or about one gallon of wash additive.

As will be described in detail below, dispensing assembly 112 may include features for drawing wash additive from bulk reservoir 158 and mixing it with water prior to directing the mixture into wash tub 108 to facilitate a cleaning operation. By contrast, dispensing assembly 112 is also capable of dispensing water only. Thus, dispensing assembly 112 may automatically dispense the desired amount of water with or without a desired amount of wash additive such that a user can avoid filling dispenser box 160 with detergent before each operation of washing machine appliance 100.

For example, as best shown in FIG. 3, washing machine appliance 100 includes an aspirator assembly 162, which is a Venturi-based dispensing system that uses a flow of water to create suction within a Venturi tube to draw in wash additive from bulk reservoir 158 which mixes with the water and is dispensed into wash tub 108 as a concentrated wash fluid preferably having a target volume of wash additive. After the target volume of wash additive is dispensed into wash tub 108, additional water may be provided into wash tub 108 as needed to fill to the desired wash volume. It should be appreciated that the target volume may be pre-programmed in controller 156 according to the selected operating cycle or parameters, may be set by a user, or may be determined in any other suitable manner.

As illustrated, aspirator assembly 162 includes a Venturi pump 164 that is fluidly coupled to both a water supply conduit 166 and a suction line 168. As illustrated, water supply conduit 166 may provide fluid communication between a water supply source 170 (such as a municipal water supply) and a water inlet of Venturi pump 164. In addition, washing machine appliance 100 includes a water fill valve or water control valve 172 which is operably coupled to water supply conduit 166 and is communicatively coupled to controller 156. In this manner, controller 156 may regulate the operation of water control valve 172 to regulate the amount of water that passes through aspirator assembly 162 and into wash tub 108.

In addition, suction line 168 may provide fluid communication between bulk reservoir 158 and Venturi pump 164 (e.g., via a suction port defined on Venturi pump 164). Notably, as a flow of water is supplied through Venturi pump 164 to wash tub 108, the flowing water creates a negative pressure within suction line 168. This negative pressure may draw in wash additive from bulk reservoir 158. When certain conditions exist, the amount of wash additive dispensed is roughly proportional to the amount of time water is flowing through Venturi pump 164.

Referring still to FIG. 3, aspirator assembly 162 may further include a suction valve 174 that is operably coupled to suction line 168 to control the flow of wash additive through suction line 168 when desired. For example, suction valve 174 may be a solenoid valve that is communicatively coupled with controller 156. Controller 156 may selectively open and close suction valve 174 to allow wash additive to flow from bulk reservoir 158 through additive suction valve 174. For example, during a rinse cycle where only water is desired, suction valve 174 may be closed to prevent wash

additive from being dispensed through suction valve 174. In some embodiments, suction valve 174 is selectively controlled based on at least one of the selected wash cycle, the soil level of the articles to be washed, and the article type.

5 According to still other embodiments, no suction valve 174 is needed at all and alternative means for preventing the flow of wash additive may be used or other water regulating valves may be used to provide water into wash tub 108.

Washing machine appliance 100, or more particularly, 10 dispensing assembly 112, generally includes a discharge nozzle 176 for directing a flow of wash fluid (e.g., identified herein generally by reference numeral 178) into wash tub 108. In this regard, discharge nozzle 176 may be positioned above wash tub 108 proximate a rear of opening 116 defined through top panel 118. Dispensing assembly 112 may be regulated by controller 156 to discharge wash fluid 178 through discharge nozzle 176 at the desired flow rates, 15 volumes, and/or detergent concentrations to facilitate various operating cycles, e.g., such as wash or rinse cycles.

20 Although water supply conduit 166, water supply source 170, discharge nozzle 176, and water control valve 172 are all described and illustrated herein in the singular form, it should be appreciated that these terms may be used herein generally to describe a supply plumbing for providing hot 25 and/or cold water into wash chamber 110. In this regard, water supply conduit 166 may include separate conduits for receiving hot and cold water, respectively. Similarly, water supply source 170 may include both hot- and cold-water supplies regulated by dedicated valves. In addition, washing 30 machine appliance 100 may include one or more pressure sensors (not shown) for detecting the amount of water and or clothes within wash tub 108. For example, the pressure sensor may be operably coupled to a side of wash tub 108 for detecting the weight of wash tub 108, which controller 35 156 may use to determine a volume of water in wash chamber 110 and a subwasher load weight.

After wash tub 108 is filled and the agitation phase of the wash cycle is completed, wash basket 114 can be drained, e.g., by drain pump assembly 130. Laundry articles can then 40 be rinsed by again adding fluid to wash basket 114 depending on the specifics of the cleaning cycle selected by a user. The impeller or agitation element 132 may again provide agitation within wash basket 114. One or more spin cycles 45 may also be used as part of the cleaning process. In particular, a spin cycle may be applied after the wash cycle and/or after the rinse cycle in order to wring wash fluid from the articles being washed. During a spin cycle, wash basket 114 is rotated at relatively high speeds to help wring fluid from the laundry articles through perforations 126. During or prior to the spin cycle, drain pump assembly 130 may operate to discharge wash fluid from wash tub 108, e.g., to an external drain. After articles disposed in wash basket 114 are cleaned and/or washed, the user can remove the articles 50 from wash basket 114, e.g., by reaching into wash basket 114 through opening 116.

Referring still to FIG. 1, a schematic diagram of an external communication system 190 will be described according to an exemplary embodiment of the present subject matter. In general, external communication system 60 190 is configured for permitting interaction, data transfer, and other communications between washing machine appliance 100 and one or more external devices. For example, this communication may be used to provide and receive operating parameters, user instructions or notifications, performance characteristics, user preferences, or any other suitable information for improved performance of washing machine appliance 100. In addition, it should be appreciated

that external communication system 190 may be used to transfer data or other information to improve performance of one or more external devices or appliances and/or improve user interaction with such devices.

For example, external communication system 190 permits controller 156 of washing machine appliance 100 to communicate with a separate device external to washing machine appliance 100, referred to generally herein as an external device 192. As described in more detail below, these communications may be facilitated using a wired or wireless connection, such as via a network 194. In general, external device 192 may be any suitable device separate from washing machine appliance 100 that is configured to provide and/or receive communications, information, data, or commands from a user. In this regard, external device 192 may be, for example, a personal phone, a smartphone, a tablet, a laptop or personal computer, a wearable device, a smart home system, or another mobile or remote device.

In addition, a remote server 196 may be in communication with washing machine appliance 100 and/or external device 192 through network 194. In this regard, for example, remote server 196 may be a cloud-based server 196, and is thus located at a distant location, such as in a separate state, country, etc. According to an exemplary embodiment, external device 192 may communicate with a remote server 196 over network 194, such as the Internet, to transmit/receive data or information, provide user inputs, receive user notifications or instructions, interact with or control washing machine appliance 100, etc. In addition, external device 192 and remote server 196 may communicate with washing machine appliance 100 to communicate similar information.

In general, communication between washing machine appliance 100, external device 192, remote server 196, and/or other user devices or appliances may be carried using any type of wired or wireless connection and using any suitable type of communication network, non-limiting examples of which are provided below. For example, external device 192 may be in direct or indirect communication with washing machine appliance 100 through any suitable wired or wireless communication connections or interfaces, such as network 194. For example, network 194 may include one or more of a local area network (LAN), a wide area network (WAN), a personal area network (PAN), the Internet, a cellular network, any other suitable short- or long-range wireless networks, etc. In addition, communications may be transmitted using any suitable communications devices or protocols, such as via Wi-Fi®, Bluetooth®, Zigbee®, wireless radio, laser, infrared, Ethernet type devices and interfaces, etc. In addition, such communication may use a variety of communication protocols (e.g., TCP/IP, HTTP, SMTP, FTP), encodings or formats (e.g., HTML, XML), and/or protection schemes (e.g., VPN, secure HTTP, SSL).

External communication system 190 is described herein according to an exemplary embodiment of the present subject matter. However, it should be appreciated that the exemplary functions and configurations of external communication system 190 provided herein are used only as examples to facilitate description of aspects of the present subject matter. System configurations may vary, other communication devices may be used to communicate directly or indirectly with one or more associated appliances, other communication protocols and steps may be implemented, etc. These variations and modifications are contemplated as within the scope of the present subject matter.

While described in the context of a specific embodiment of vertical axis washing machine appliance 100, using the

teachings disclosed herein it will be understood that vertical axis washing machine appliance 100 is provided by way of example only. Other washing machine appliances having different configurations, different appearances, and/or different features may also be utilized with the present subject matter as well, e.g., horizontal axis washing machine appliances. In addition, aspects of the present subject matter may be utilized in a combination washer/dryer appliance.

Now that the construction of washing machine appliance 100 and the configuration of controller 156 according to exemplary embodiments have been presented, an exemplary method 200 of operating a washing machine appliance will be described. Specifically, method 200 may be used to implement an automated spin cycle in a washing machine appliance, such as the washing machine appliance 100. Although the discussion below refers to the exemplary method 200 of operating washing machine appliance 100, one skilled in the art will appreciate that the exemplary method 200 is applicable to the operation of a variety of other washing machine appliances, such as horizontal axis washing machine appliances. In exemplary embodiments, the various method steps as disclosed herein may be performed by controller 156 or a separate, dedicated controller.

Specifically, method 200 includes, at step 210, receiving a command to perform an automated spin cycle of a washing machine appliance that terminates based on monitoring a reduction of a remaining moisture content of a load of clothes within a wash basket. In this regard, continuing the example above, a user may select or command washing machine appliance 100 to perform a spin cycle that terminates when a target reduction of the remaining moisture content is reached, thereby ensuring proper spin out of the load of clothes without having unnecessarily long spin times and reducing energy usage. In general, the terms "automated spin cycle" and the like may be used generally herein to refer to spin cycles of a washing machine appliance that are not based simply on fixed spin times/speeds as in conventional washing machines. By contrast, the speed and duration of automated spin cycles may be automatically adjusted based on sensed parameters such as the estimated reduction in the remaining moisture content or drawn motor power.

It should be appreciated that the command to perform the automated spin cycle may be obtained by controller 156 of washing machine appliance 100 in any suitable manner. In this regard, for example, conventional washing machines may provide for the selection of a "low" spin cycle or a "high" spin cycle. However, these selections result in the execution of a spin cycle that is based only on speed and/or time. By contrast, commands according to the present subject matter may initiate a novel automated spin cycle as described in detail below. It should be appreciated that these commands for the automated spin cycle may be provided through one or more input selectors 152 on control panel 150. According to still other embodiments, the command to perform an automated spin cycle may be provided from external device 192 (e.g., via network 194) or the command may be received in any other suitable manner.

Step 220 may generally include initiating the automated spin cycle by operating a motor to spin a wash basket to a first speed. In this regard, drive motor 140 of washing machine appliance 100 may operate drive motor 140 to accelerate wash basket 114 to a first speed that is lower than a terminal or standard spin speed for a given operating cycle. For example, according to example embodiments, the first speed may be between about 500 and 800 revolutions per minute (RPM), between about 600 and 750 RPM, or about

700 RPM. Other suitable first speeds are possible and within the scope of the present subject matter.

Step 230 may generally include performing a first acceleration by operating the motor to accelerate the wash basket from the first speed to a second speed. In general, the second speed may be an elevated speed relative to the first speed and may correspond to a standard spin speed associated with a standard spin cycle. For example, according to example embodiments, the second speed may be between about 700 and 1000 revolutions per minute (RPM), between about 750 and 900 RPM, or about 800 RPM. Other suitable second speeds are possible and within the scope of the present subject matter.

Step 240 may generally include obtaining a first average motor power of the motor while performing the first acceleration. In this regard, controller 156 may monitor the power output of drive motor 140 while accelerating wash basket 114 from the first speed to the second speed. According to alternative embodiments, other methods for determining motor power may be used while remaining within the scope of the present subject matter. Although the average motor power is described as being used herein, it should be appreciated that any other representation of power used during the first acceleration may be used while remaining within the scope of the present subject matter.

Although FIG. 5 shows the basket speed being accelerated directly to the second speed and then being decreased to the first speed before accelerating back to the second speed, it should be appreciated that aspects of the present subject matter are intended to include measuring the average motor power during any acceleration period from the first speed to the second speed. For example, FIG. 5 illustrates six instances of such an acceleration, any of which may be used to obtain the average motor power. In addition, it should be appreciated that any suitable method of determining basket speed may be used while remaining within the scope of the present subject matter. For example, according to example embodiments, basket speed may be measured using a magnet and hall-effect sensor.

Step 250 may generally include decelerating the wash basket to the first speed. In this regard, drive motor 140 may stop applying power, reduce its power output, or reverse the power output to allow wash basket 114 to coast back down to the first speed. Step 260 may include performing a second acceleration by operating the motor to accelerate the wash basket from the first speed to the second speed (e.g., similar to step 230). Step 270 may include obtaining a second average motor power of the while performing second acceleration (e.g., similar to step 240). This process of acceleration and decelerating the wash basket 114 may be repeated in order to obtain useful information regarding the reduction in the remaining moisture content of the load of clothes and to determine a desired time to terminate the automated spin cycle, as described in more detail below.

In this regard, although two acceleration periods are described herein, it should be appreciated that aspects of the present subject matter may include multiple additional periods where the wash basket is accelerated and the motor power is monitored. For example, as illustrated in FIG. 5, the motor power and basket speed during an automated spin cycle is illustrated. As described in more detail below, by monitoring the average motor power exerted during the acceleration periods of wash basket, useful information regarding the reduction in the remaining moisture content within the load of clothes may be obtained to facilitate improved performance of the automated spin cycle.

In addition, method 200 may further include a process for accounting for system friction or other factors that may affect basket speed and/or motor power. For example, method 200 may further include a step including obtaining power measurements at dwell speeds (e.g., the speed between accelerating at step 230 and decelerating at step 250). The power measurements obtained during these dwells may be used to determine the power needed to maintain basket speed and thus provide an estimate of the friction or resistive forces exerted by a particular load within a particular machine.

Specifically, step 280 may include determining that a reduction in the remaining moisture content of a load of clothes exceeds a target reduction in the remaining moisture content based at least in part on the first average motor power and the second average motor power. In this regard, as shown for example in FIG. 6, an example relationship between motor power and the reduction in the remaining moisture content of an example load of clothes is illustrated. Each dot on the motor power line in FIG. 6 may represent the average motor power during an acceleration period. Similarly, each dot on the remaining moisture content line may indicate the average remaining moisture content during that acceleration period.

For example, determining that the reduction in the remaining moisture content of the load of clothes exceeds the target reduction in the remaining moisture content based on the first average motor power and the second average motor power may include determining a power difference between the first average motor power and the second average motor power and determining that this difference falls below a predetermined difference threshold. In this regard, the predetermined difference threshold may be set by manufacturer or by a user as a fixed value associated with the target reduction in the remaining moisture content. In other words, when the average power difference between the acceleration periods falls below a predetermined level or approaches zero, it may be assumed that no further water is going to be extracted from the load of clothes and that the target reduction in the remaining moisture content has been reached. The predetermined difference threshold may be adjusted, e.g., based on a user's sensitivity to remaining moisture, energy consumption, time-demands, etc.

In general, method 200 may include monitoring the motor power, e.g., as a proxy for the reduction in the remaining moisture content. When the reduction in the remaining moisture content reaches a desired level, the automated spin cycle may terminate automatically without user intervention and independently of any timer associated with conventional spin cycles. In this regard, step 290 may include stopping the automated spin cycle in response to determining that the reduction in the remaining moisture content has reached a value large enough to terminate the automated spin cycle, e.g., the reduction exceeds the target reduction in the remaining moisture content. By contrast, method 200 may also include continuing the spin cycle (e.g., by repeatedly accelerating and decelerating the wash basket while monitoring motor power) in response to determining that the reduction in the remaining moisture content falls below the target reduction in the remaining moisture content.

For example, the motor power may be used to estimate the reduction in the remaining moisture content of the load of clothes and the automated spin cycle may terminate when a target reduction in the remaining moisture content is reached. According to example embodiments, the target reduction in the remaining moisture content may be based on a variety of factors, such as fabric type, load size, etc. As

shown in FIG. 6, there may be a substantially proportional relationship between the average motor power required to accelerate the basket and the remaining moisture content. In this regard, as more water sheds from the load and the remaining moisture content decreases, less power may be required for drive motor 140 to accelerate the wash basket 114 back up to the second speed. Although a proportional relationship is illustrated, it should be appreciated that this relationship may be embodied in any other suitable relationship, e.g., such as a mathematical relationship, a regression equation, a lookup table, etc. This relationship may be determined empirically, theoretically, or in any other suitable manner.

Notably, there may be certain situations where the reduction in the remaining moisture content does not reach the target reduction in the remaining moisture content despite repeated and continuous performance of the automated spin cycle. For example, specific load types or other drainage issues may result in a remaining moisture content that does not track a profile similar to that shown in FIG. 6. Accordingly, method 200 may further include determining that a predetermined amount of time has passed since the initiation of the automated spin cycle and stopping the spin cycle regardless of the reduction in the remaining moisture content. In this regard, this may serve as a debounce procedure that prevents damage to the appliance, the load of clothes, or extended spin cycle times and energy usage.

FIG. 4 depicts steps performed in a particular order for purposes of illustration and discussion. Those of ordinary skill in the art, using the disclosures provided herein, will understand that the steps of any of the methods discussed herein can be adapted, rearranged, expanded, omitted, or modified in various ways without deviating from the scope of the present disclosure. Moreover, although aspects of method 200 are explained using washing machine appliance 100 as an example, it should be appreciated that this method may be applied to the operation of any suitable laundry appliance, such as another washing machine appliance.

As explained herein, aspects of the present subject matter are generally directed to a method for sensing a reduction in a remaining moisture content (RMC) based on motor power consumption in a top load washing machine. The method may include periodically decreasing and increasing the basket speed while measuring motor power. The method may include capturing the average motor power upon initial acceleration of the basket from a speed lower than a terminal speed (speed 1) to the terminal speed (e.g. 700 to 800 RPM). The method allows the speed to decrease to speed 1, then increases back to terminal speed at various time intervals and records average motor power while accelerating. The proportional relationship between the motor power and remaining moisture content (RMC) of the clothing load is used, and the cycle may be stopped once the desired drop in RMC has been achieved (based on relationship between the reduction in motor power and the reduction in RMC). This value may be derived from previously sensed data such as fabric type and load size from earlier in the cycle. If the motor power reduction is not sufficient to achieve the desired RMC reduction, the cycle may be once again repeated. Aspects of the present subject matter may also be directed to a top load washing machine that provides a user selectable option/button (or selected by default) for automatic or optimum spin time based on remaining moisture content (RMC) reduction of the load. The spin time may be reduced or increased based on the live reduction in the remaining moisture content (RMC) measurements of the clothing load.

In addition, the method may include optimizing the RMC results and spin time based on the load size or type.

This written description uses examples to disclose the invention, including the best mode, and also to enable any person skilled in the art to practice the invention, including making and using any devices or systems and performing any incorporated methods. The patentable scope of the invention is defined by the claims, and may include other examples that occur to those skilled in the art. Such other examples are intended to be within the scope of the claims if they include structural elements that do not differ from the literal language of the claims, or if they include equivalent structural elements with insubstantial differences from the literal language of the claims.

What is claimed is:

1. A washing machine appliance defining a vertical direction, a lateral direction, and a transverse direction, the washing machine appliance comprising:

a wash tub positioned within a cabinet;
a wash basket rotatably mounted within the wash tub for receiving a load of clothes;
a motor mechanically coupled to the wash basket; and a controller operably coupled to the motor, the controller being configured to:
initiate a spin cycle by operating the motor to spin the wash basket to a first speed;
perform a first acceleration by operating the motor to accelerate the wash basket from the first speed to a second speed;
obtain a first average motor power of the motor while performing the first acceleration;
decelerate the wash basket to the first speed;
perform a second acceleration by operating the motor to accelerate the wash basket from the first speed to the second speed;

obtain a second average motor power of the motor while performing the second acceleration;
determine that a reduction in a remaining moisture content of the load of clothes exceeds a target reduction in the remaining moisture content based at least in part on the first average motor power and the second average motor power; and stop the spin cycle in response to determining that the reduction in the remaining moisture content exceeds the target reduction in the remaining moisture content.

2. The washing machine appliance of claim 1, wherein the first speed is between about 500 and 800 revolutions per minute (RPM).

3. The washing machine appliance of claim 1, wherein the second speed is between about 700 and 1000 revolutions per minute (RPM).

4. The washing machine appliance of claim 1, wherein the target reduction in the remaining moisture content may be based on fabric type or load size.

5. The washing machine appliance of claim 1, wherein determining that the reduction in the remaining moisture content of the load of clothes exceeds the target reduction in the remaining moisture content based at least in part on the first average motor power and the second average motor power comprises:

determining a power difference between the first average motor power and the second average motor power; and determining that the power difference falls below a predetermined difference threshold.

6. The washing machine appliance of claim 1, wherein the controller is further configured to:

15

perform a third acceleration by operating the motor to accelerate the wash basket from the first speed to the second speed;
 obtain a third average motor power of the motor while performing the third acceleration; and
 determine that the reduction in the remaining moisture content of the load of clothes exceeds the target reduction in the remaining moisture content based at least in part on the first average motor power, the second average motor power, and the third average motor power.

7. The washing machine appliance of claim 1, wherein determining that the reduction in the remaining moisture content of the load of clothes exceeds the target reduction in the remaining moisture content based at least in part on the first average motor power and the second average motor power comprises:

estimating the reduction in the remaining moisture content of the load of clothes based on the first average motor power and the second average motor power.

8. The washing machine appliance of claim 7, wherein estimating the reduction in the remaining moisture content comprises utilizing a mathematical relationship between an average motor power and the reduction in the remaining moisture content.

9. The washing machine appliance of claim 1, wherein the controller is further configured to:

receive a command to perform an automated spin cycle that terminates based on the reduction in the remaining moisture content.

10. The washing machine appliance of claim 9, wherein the washing machine appliance further comprises:

a user interface panel comprising a user input for providing the command to perform the automated spin cycle.

11. The washing machine appliance of claim 9, wherein the controller is in operative communication with a remote device through an external network, and wherein the command to perform the automated spin cycle is provided through the remote device.

12. The washing machine appliance of claim 1, wherein the controller is further configured to:

determine that a predetermined amount of time has passed since the initiation of the spin cycle; and stop the spin cycle regardless of the reduction in the remaining moisture content.

13. The washing machine appliance of claim 1, further comprising:

a magnet and hall-effect sensor that is used to obtain the basket speed of the wash basket.

14. The washing machine appliance of claim 1, wherein the controller is further configured to:

obtain an average dwell motor power of the motor between the steps of decelerating the wash basket and performing a subsequent acceleration; and estimating a system friction or other resistive forces that affect the basket speed or an average motor power.

15. The washing machine appliance of claim 1, wherein the controller is further configured to:

16

determining that the reduction in the remaining moisture content of the load of clothes remains below the target reduction in the remaining moisture content based at least in part on the first average motor power and the second average motor power; and continue the spin cycle.

16. A method of operating a washing machine appliance, the washing machine appliance comprising a wash tub positioned within a cabinet, a wash basket rotatably mounted within the wash tub for receiving a load of clothes, and a motor mechanically coupled to the wash basket, the method comprising:

initiating a spin cycle by operating the motor to spin the wash basket to a first speed;

performing a first acceleration by operating the motor to accelerate the wash basket from the first speed to a second speed;

obtaining a first average motor power of the motor while performing the first acceleration;

decelerating the wash basket to the first speed; performing a second acceleration by operating the motor to accelerate the wash basket from the first speed to the second speed;

obtaining a second average motor power of the motor while performing the second acceleration;

determining that a reduction in the remaining moisture content of the load of clothes exceeds a target reduction in the remaining moisture content based at least in part on the first average motor power and the second average motor power; and

stopping the spin cycle in response to determining that the reduction in the remaining moisture content exceeds the target reduction in the remaining moisture content.

17. The method of claim 16, wherein determining that the reduction in the remaining moisture content of the load of clothes exceeds the target reduction in the remaining moisture content based at least in part on the first average motor power and the second average motor power comprises:

determining a power difference between the first average motor power and the second average motor power; and determining that the power difference falls below a pre-determined difference threshold.

18. The method of claim 16, wherein determining that the reduction in the remaining moisture content of the load of clothes exceeds the target reduction in the remaining moisture content based at least in part on the first average motor power and the second average motor power comprises:

estimating the reduction in the remaining moisture content of the load of clothes based on the first average motor power and the second average motor power.

19. The method of claim 18, wherein estimating the reduction in the remaining moisture content comprises utilizing a mathematical relationship between an average motor power and the reduction in the remaining moisture content.

20. The method of claim 16, further comprising:

receiving a command to perform an automated spin cycle that terminates based on the reduction in the remaining moisture content.
